UNITED STATES PATENT OFFICE.

FERDINAND STOLZ, OF DETROIT, MICHIGAN.

BAKER'S OVEN.

SPECIFICATION forming part of Letters Patent No. 517,251, dated March 27, 1894.

Application filed July 21, 1893. Serial No. 481,145. (No model.)

To all whom it may concern:

Be it known that I, FERDINAND STOLZ, a subject of the Emperor of Germany, residing at Detroit, in the county of Wayne and State 5 of Michigan, have invented certain new and useful Improvements in Bakers' Ovens, of which the following is a specification, reference being had therein to the accompanying drawings.

10 This invention refers more particularly to an improved attachment for bakers' oven designed for the purpose of lighting the interior thereof and providing it with steam for producing an improved product, all as more 15 fully hereinafter described and particularly set forth in the claims.

In the drawings, Figure 1 is an elevation of a baker's oven of known construction to which my attachment is applied. Fig. 2 is 20 an enlarged vertical section on line $x-x$ in Fig. 1. Fig. 3 is a horizontal section on line $y-y$ in Fig. 2. Fig. 4 is a similar horizontal section on line $z-z$ in Fig. 2. Fig. 5 is a detached perspective view of the bow window.

25 The oven which I show in the drawings is of the usual kind, which has an arched brick chamber A in which light wood or sticks are burned inside, to heat the interior of the chamber preparatory to baking, but my invention applies as well to any kind of oven 30 for bakers' use.

My invention consists in an improved attachment to light the interior of the chamber and also to furnish steam into the interior 35 while baking bread which it is well understood improves the product. To this end I form in the oven at any suitable place preferably in proximity to or beside the usual oven door B, an aperture into the oven in 40 which I place my attachment. This consists of a cast iron frame C which forms a lining for the opening in the wall, and which has three half-circular projections D' D² extending into the oven A. The vertical dis- 45 tance between these three half circular projections or shelves is such that the lower shelf D rests upon the bottom of the oven, the top shelf D² projects immediately under the arch of the oven and the intermediate 50 shelf D' is about midway between. Between the lower and middle shelves a boiler E is placed and fills the opening between the two

shelves, being made to this end substantially of semicylindrical shape, its inward displacement being prevented by annular flanges a 55 running around the shelves.

A supply pipe F communicates through the opening in front into the top of the boiler and has a valve G for closing it, and this supply pipe communicates with the vertical fill- 60 tube H which terminates at the top in a funnel I and is connected to the supply pipe through a union coupling F'. In a similar manner a steam pipe J extends from the boiler through the aperture in front and is 65 connected by a return bend with the return pipe K into the oven, the pipes being connected together by a union coupling L and a valve M is placed in this steam pipe. The object of this boiler is to generate steam. To 70 this end when the oven is being heated the boiler is filled with water which is heated by the fire in the oven and by the heat of the oven during the subsequent baking thus generating steam which is admitted into the oven 75 by closing the valve G and opening the valve M. If not wanted the valve M may be closed and the valve G opened.

The whole boiler may be withdrawn for inspection and repair by unscrewing the couplings F' and L when it can be withdrawn from 80 its position through the opening formed by the casing.

For the purpose of lighting the interior of the oven a bow window N of suitable shape 85 to form a closing medium between the upper shelf D² and intermediate shelf D' is inserted between the two and held in place against inward displacement by suitable annular flanges b b formed around the respective 90 shelves. This bow window is constructed in the form of a metallic skeleton frame with mica windows O and with rearwardly projecting handles P, whereby it may be readily withdrawn when not needed. When in place, 95 as shown in Fig. 2, this bow window projects inside the oven and permits the use of a lamp placed so far inside as to light the whole interior. For the purpose of suitable draft for the lamp I place a ventilator pipe Q through 100 the top shelf D² which ventilating pipe I lead into the chimney of the oven. In front of the opening which contains the bow window, I provide a door R for closing the opening

while the oven is heating, the bow window being preferably removed during such time.

What I claim as my invention is—

1. In a baker's oven, the combination with a suitable casing forming an aperture into the oven, of the inwardly projecting shelves D D' D² on said casing, the boiler E and bow window N removably supported between said shelves, substantially as described.
2. In a baker's oven, the combination of the frame C forming an aperture through the wall into the oven, the inwardly projecting shelves D D' D², the semi-cylindrical boiler E

removably supported between the shelves D D', the bow window N provided with the handles P removably secured between the shelves D' D², the door R and the supply and steam connection of the boiler E, all combined and arranged, substantially as described. 15

In testimony whereof I affix my signature in 20 presence of two witnesses.

FERDINAND STOLZ.
